UNITED STATES PATENT OFFICE.

ALBERT BLATTMANN, OF NORTH ADAMS, MASSACHUSETTS.

DESIGN FOR A CUFF-HOLDER.

47,583.

Specification for Design.

Patented July 20, 1915.

Application filed April 1, 1915. Serial No. 18,604. Term of patent 14 years.

To all whom it may concern:

Be it known that I, ALBERT BLATTMANN, a citizen of the United States, residing at North Adams, in the county of Berkshire, State of Massachusetts, have invented a new, original, and ornamental Design for a Cuff-Holder, of which the following is a specification, reference being had to the accompanying drawing, forming part thereof.

The figures are: 1. A perspective view of a cuff holder, showing my new design; 2. An edge view thereof.

I claim:

The ornamental design for a cuff holder, as shown.

ALBERT BLATTMANN.

Witnesses:

ANNA M. BLATTMANN,

LILY BLATTMANN.
